UNITED STATES PATENT OFFICE

106,999

DESIGN FOR A WINDOW SHADE GUARD

Robert F. Willis, Detroit, Mich.

Application October 12, 1936, Serial No. 65,274

Term of patent 7 years

To all whom it may concern:

Be it known that I, Robert F. Willis, a citizen of the United States of America, residing at Detroit, county of Wayne and State of Michigan, have invented a new, original, and ornamental Design for a Window Shade Guard, of which the following is a specification, reference being had to the accompanying drawing, forming a part thereof, wherein:

I claim:

The ornamental design for a window shade guard, as shown.

ROBERT F. WILLIS.
